W. L. O'BRIEN

REAMING TOOL

Filed Sept. 15, 1922

Inventor
William L. O'Brien,

By Faulmin & Faulmin

Attorneys

UNITED STATES PATENT OFFICE.

WILLIAM L. O'BRIEN, OF DAYTON, OHIO.

REAMING TOOL.

Application filed September 15, 1922. Serial No. 588,421.

To all whom it may concern:

Be it known that I, WILLIAM L. O'BRIEN, a citizen of the United States, residing at Dayton, in the county of Montgomery and 5 State of Ohio, have invented certain new and useful Improvements in Reaming Tools, of which the following is a specification, reference being had therein to the accompanying drawing.

10 My invention relates to a tool and in particular to a reaming tool and a holder therefor.

15 It is my object to provide a floating tool holder for a reaming tool in which the holder is held stationary and the work turns relatively to the reamer.

20 It is my object to provide an universal adjustment of the tool holder and its supporting casing which will permit of the free movement of the tool holder but which will prevent the twisting of the tool holder due to the torque imparted thereto.

25 It is a further object to provide a constant automatic adjustment of the reaming tool and its holder to the work to take up any inequality of the position of the holder relative to the work so that the hole in the work will be reamed accurately.

30 It is a further object to provide means of limiting the degree to which this automatic adjustment will take place.

It is a further object to provide means of quickly clamping in position and securing a hold on the reaming tool.

35 Referring to the drawings.

Fig. 1 is a side elevation of the complete tool partially in section;

Fig. 2 is a front elevation of the assembled tool and holder;

40 Fig. 3 is a detail partially in section of the universal joint between the supporting casing and the tool holder;

Fig. 4 is a side elevation in detail of the torque pin used in the universal joint between the tool holder and the supporting casing;

Fig. 5 is an end elevation of the universal connection of the tool holder and casing.

Referring to the drawings in detail, 1 is 50 a cylindrical casing having chamber 2 therein. At one end it is provided with the narrow throat 3. This throat has communicated with it through the walls the passageway 4 into which projects the posi-

tioning pin 5 which fits freely therein. 55 This pin is carried by the ball head 6 of the tool holder 7. This head 6 is provided with a rounded end 8 and fits within the restricted passageway 3. The tool holder 7 is of greater diameter than the head 6, and 60 fits within the chamber 2 which permits of clearance between 7 and 1.

The left hand end of 1 is provided with a chamber 9 in which fits the tool holder head 10. 65

7 is provided with a chamber 11 for the reception of the shank of the reaming tool. This arrangement is shown where a part of the wall of 7 is broken away. The head 10 has a similar chamber for the reception 70 of the supporting end of the reaming tool, this chamber being designated as 12. In the arrangement of the reaming tool 13 shown in Figs. 1 and 2 the supporting shaft of the tool only extends into 12, but other 75 types of tools with different sizes of shafts may have their supporting shafts projected to 11.

The head 10 is provided with a collar 14 split at 15. The split collar is adapted 80 to have its halves drawn together by the bolt 16 so that the supporting shaft of the reaming tool 13, such as shaft 17, may be located in position relative to the tool holder. 85

There is provided a yieldingly adjustable member to keep the floating tool holder 7 automatically in a position where the reamer 13 will follow the proper course through the work and ream in a floating engagement 90 therewith.

This arrangement consists of a contact button 18 which has a limiting head 19. 95 18 engages with the head 10 to move the tool holder while 19 limits its movement by coming in contact with the shoulder 20 in the spring chamber 21. This spring chamber is located in a flange 22 carried at the left hand end of 1. Within this chamber and engaging with the head 19 is 100 a spring 23, the tension on which may be adjusted by the screw plug 24.

As the tool holder moves about the universal joint at its right hand side, it is retained in a predetermined position yieldingly by 18, 19 and 23. 105

Returning to the universal joint which forms the connection between 1 and 7 there

is provided aperture 25 for the pin 26 carried by the torque pin 27 which is flat and through which passes the pin 5 at right angles through the aperture 28. This pin 27 5 has a head 29 which is rotatably mounted in the aperture 30 in 1. The flat portion of 27 fits in a slot 31 in 6 and thus prevents 6 rotating about the major axis of the assembly to resist the torque action imparted 10 to the reaming tool, but this does not prevent the lateral or vertical movement within a limited degree of the tool holder 7 and its head 6 relative to 1, thus permitting 15 of an efficient operation of the automatic means for maintaining the alignment of the reamer and its floating engagement with the work upon which it is operating.

While I have shown and described certain features as constituting my invention, it will be understood that parts have been shown for purposes of illustration only, and that I do not desire to be limited to such details, as obvious modifications will occur 25 to a person skilled in the art.

Having thus fully described my invention,

what I claim as new and desire to secure by Letters Patent, is:—

In a floating tool holder, a tubular casing provided at one end with pairs of intersecting apertures, the axes of which intersect the bore of the casing, a tool holder arranged in the casing and having a ball head at one end provided with a kerf dividing the head into two tines; said tines 35 being provided with aligned apertures coaxial with the axes of one pair of the apertures in the casing, a pivot pin rotatably mounted in the other pair of apertures in the casing and having a flat central portion snugly and slidably engaging the side surface of said kerf, and a second pivot pin passing through one pair of apertures in the casing, through the apertures in the tines and through the first mentioned pivot 45 pin, and functioning to lock the tool holder and first mentioned pivot pin in the casing.

In testimony whereof, I affix my signature.

WILLIAM L. O'BRIEN.
